DESIGN FOR A SNAP LOCK FOR A BAG OR SIMILAR ARTICLE

Herbert Rubin, New York, N. Y.

Application January 10, 1938, Serial No. 74,175

Term of patent 3½ years

To all whom it may concern:

Be it known that I, Herbert Rubin, a citizen of the United States, residing at 984 Sheridan Avenue, Bronx, New York, have invented a new, original, and ornamental Design for a Snap Lock for a Bag or Similar Article, of which the following is a specification, reference being had to the accompanying drawing, forming part thereof, wherein:

Figure 1 is a plan view of a snap lock for a bag or similar article, showing my new design, and

Fig. 2 is a side view thereof.

I claim:

The ornamental design for a snap lock for a bag or similar article, substantially as shown.

HERBERT RUBIN.
